J. G. GALLOWAY

COMPARTMENT BAG

Filed Nov. 22, 1924

INVENTOR

June G. Galloway

BY

Albert Bell

ATTORNEYS

UNITED STATES PATENT OFFICE.

JESSE G. GALLOWAY, OF FALMOUTH, KENTUCKY.

COMPARTMENT BAG.

Application filed November 22, 1924. Serial No. 751,450.

To all whom it may concern:

Be it known that I, JESSE G. GALLOWAY, a citizen of the United States, and a resident of Falmouth, in the county of Pendleton, and State of Kentucky, have invented certain new and useful Improvements in Compartment Bags, of which the following is a full, clear, and exact description, reference being had to the accompanying drawing, forming part of this specification.

My invention relates to bags and satchels having a removable compartment element in the lower portion thereof. Among particular uses for my structure is the provision in a hand bag of a means for retaining a liquid container for use by undertakers and embalmers, although my structure is suitable for a wide range of purposes.

It is my object to provide a device for supporting a base, removable by adjustment from within the bag, and of holding up with the base a container of any desired size or shape. It is my object to provide for the support of the base from a frame that forms the bottom of the compartment above that in which the liquid container is placed, and also to provide for the support of the frame by means of links which connect the frame with the portion of the hand bag near the handles and the closing lips of the bag.

The several devices of my invention which provide the several supports are within the bag and are not exposed from the outside. My bag has no external structure to distinguish it from any larger sized bag or satchel.

I attain the foregoing objects with this concealed structure by the mechanism illustrated in the accompanying drawing, in which:

40 Figure 1 represents a side perspective with a cutaway portion revealing the inner structure.

Figure 2 is a plan view of the open bag, and

45 Figure 3 is a longitudinal section on line 3, 3 of Figure 2, showing the lining of the upper compartment which conceals the mechanism below it. Similar numbers refer to similar parts throughout the several 50 views.

The bag indicated generally at 1, is no different from other bags of the same type except that it has no bottom rigidly secured thereto. The type of bag selected for illustration of my invention is merely one convenient form to which the invention may be

applied. A metal reinforcement 1^c may be arranged about the open bottom of the bag.

The base 2 is made of a shape to fit the open bottom of the bag proper, and the structures to be described, are those which I prefer to employ in holding the base in place.

The false bottom of the bag in the form selected for illustration, is provided by a frame formed of metal strips 4, into a rectangular shape, with cross bars 4^a for strengthening. An inner lining 5 is secured in the usual manner within the top of the bag, and lies over or is secured by stitching 70 or otherwise to the framework forming the false bottom, thus forming a compartment 6 in the upper portion of the bag.

In the drawings I have illustrated a metal vessel 15, located between the removable base and the central false bottom, although it will be understood that other devices may be placed into this space, or it may be lined and used as a second compartment for clothing, instruments, samples or the like. The 80 metal vessel serves the purpose of containing the fluid matter resulting from the embalming process, so that the undertaker can do his work at the home and remove the fluids without distress to the family. This vessel 85 is of special shape having meeting lines of top, bottom and sides rounded and the top sloping to the middle to the filler cap 15^a. The vessel may be kept perfectly clean because of this structure and is otherwise rectangular to give it large capacity.

Great strength is called for in the mode of support of the removable base, as the weight of the fluids and the heavy metal vessel is considerable.

I have provided for support of the base from the false bottom, and support of the false bottom from the portions of the bag adjacent the opening thereof, so that the weight is supported from the top of the bag 100 where the carrying handles are mounted, which is always made very stout and strong in bag and satchel construction.

Thus I secure the handles 1^a in the form illustrated by means of pieces 1^b of heavy 105 leather or other material stitched to the bag. Rings 8 are riveted through the leather pieces 1^b, and are four in number, and hung on these rings are supporting strips 7, 110 which are bent around to small loops 7^a, that are themselves soldered and riveted into the false bottom frame.

The false bottom frame has slots 13, at the central portion of the two sides thereof, through which slide the operating bars 9. The bars 9 have hinged to their lower ends 5 a pair of links 9^a, which are each hinged to suspending bars 14^a.

The suspending bars are bent around loops 14^b, secured on the underside of the false bottom frame, the same as the loops 7^a. 10 The links extend beyond the bars 14^a, and their ends act as fingers to engage under the bent up ends 14 of cross straps 14^c, secured rigidly to the removable base.

The operating bars have a pair of lugs 15 10 and 11 thereon, which co-operate with cotter pins 12 to hold the bars in adjusted position. The lining in the upper compartment is slotted to permit the ends 12^a of the bars 14^a to protrude into the interior of the 20 compartment, from which point they are operated by the user.

The operation is as follows:—Starting with the device fully assembled and the metal vessel in place and held by the mechanisms described, with the cotter pins set into the slots in the false bottom frame, so as to hold lugs 11 over far enough to engage the limiting walls of the slots, the operator first removes the cotter pins, and then lifts up 30 on the operating bars. This results in swinging inwardly the two supporting bars linked to each operating bar, and withdraws the ends of the links from engagement under the bent up ends of the cross straps 14^c. 35 The bag can then be lifted away from the base piece and the can removed for use. It is best at this point to lift the operating bars far enough for their lugs 10 to come through the slots and then to drop the cotter 40 pins into the slots to hold the bars up and the links out of engaging position.

To place the device into assembly again, the vessel is set onto the base, and the bag set over the vessel and base. The cotter 45 pins are removed and the operating bars pushed down. This thrusts the ends of the links into position under the bent up ends of the cross straps on the base, and holds the base in place.

50 The bag has no seams along the side, and the observer cannot tell that it is anything more than an ordinary satchel or bag.

The device for holding the base removably in place, is naturally subject to wide variation, and I believe that my device is 55 the first instance in the art in which a removable base is provided in a satchel or bag, that has a false bottom well above the base.

Having thus described a typical instance where my invention may be employed, what 60 I claim as new and desire to secure by Letters Patent, is:—

1. A portable hand bag having an open bottom, a separate base adapted to close said bottom, a false bottom within the bag located above the open bottom thereof, sufficiently to leave a space for insertion of desired articles, and means for removably securing said base in the bottom of the bag, said means being positioned so as to be 70 operable from within the bag above the false bottom thereof.

2. In a portable hand bag, a framework of strips, a removable compartment element supported by said strips, said strips supported from a point near the closing lips of the bag. 75

3. In a bag, a framework of strips, a removable compartment element supported by said strips, said strips supported from a point near the closing lips of the bag, and said removable compartment element released and retained from a point within the upper compartment of the bag. 80

4. A bag having a removable base, a concealed lower compartment within the bag above the removable base, a concealed framework of strips supporting the removable base, and means for releasing or retaining said base from within an upper compartment of the bag. 85

5. A bag of usual outward appearance, a concealed lower compartment within the bag above a removable base and concealed mechanism operated from within said bag where- 95 by the base is retained and released.

6. A bag of usual outward appearance, a concealed compartment in the lower portion thereof above a base of the bag, and means interiorally located for the release or 100 tenure of the base, outwardly from the bottom of the bag.

JESSE G. GALLOWAY.
